TO THE D. E. WHITON MACHINE CO., OF NEW LONDON, CONNECTICUT, A CORPO-
RATION.

STEAM-TURBINE.

1,384,286.

Specification of Letters Patent. Patented July 12, 1921.

Application filed March 13, 1920. Serial No. 365,589.

To all whom it may concern:

Be it known that we, LUCIUS E. WHITON and HENRY B. LEE, citizens of the United States, residing at New London, in the county of New London and State of Connecticut, have invented a new and useful Improvement in Steam-Turbines; and we do hereby declare the following, when taken in connection with the accompanying drawings and the characters of reference marked thereon, to be a full, clear, and exact description of the same, and which said drawings constitute part of this application, and represent, in—

15 Figure 1, a view in side elevation of a steam-turbine embodying our invention.

Fig. 2, a plan view thereof looking in the direction of the arrow A, a portion of the upper casing-member being broken away, 20 and the parts so exposed being shown in section on the curved line 2—2 of Fig. 1.

Fig. 3, a view of the turbine in vertical transverse section, the rotor being shown in elevation, with its upper portion partly 25 broken away.

Fig. 4, a detached perspective sectional view of the upper casing-member.

Fig. 5, a detached view of one of the primary nozzles.

30 Fig. 6, a corresponding view of one of the secondary nozzles.

Our invention relates to an improvement in steam-turbines, the object being to provide improved means for mounting and positioning their nozzles, whereby the same are positively held against displacement in use by the impact of steam under high tension or by the vibration of the parts of the turbine.

40 With these ends in view, our invention consists in a steam-turbine having certain details of construction as will be hereinafter described and pointed out in the claims.

For the illustration of our invention, we 45 have chosen to show it as applied to a turbine having primary and secondary nozzles or jets, though it is equally applicable to turbines having only primary nozzles.

As herein shown, the rotor 3, which may 50 be of any approved construction, is located in a steam-chamber 4 formed within a two-part horizontally split casing, consisting of an upper member 5 and a lower member 6,

which latter forms the base and carries the bearings 7 of the rotor-shaft 8.

Coming now to our present improvement, the inner face of the left-hand side wall of the steam-chamber 4 is formed with an inwardly projecting, two-part, concentric offset 9, the two halves of which are respectively formed within the upper and lower halves 5 and 6 of the casing. The said offset contains an annular steam-passage 10 of rectangular cross-section to which steam is supplied through an intake-port 11 in the lower or base-member 6 of the casing. The vertical or inner face of the said concentric offset 9 is formed with four, equi-distant, horizontal, round holes 12, the inner ends of which are encircled by shallow, circular, position-recesses 13 intersected and connected by a shallow, virtually annular, positioning-groove 14 comprising four segments united by the said positioning-recesses 13.

The said positioning-recesses are just large enough in diameter to receive circular hubs 15 formed at the inner ends of the primary steam-nozzles 16, which may be of any approved construction so long as they are furnished with outwardly turned positioning-fingers 17 adapted to be entered into the concentric positioning-groove 14, whereby the nozzles are unalterably positioned in the steam-chamber 4 in proper relation to the buckets of the rotor 3, and held against lateral displacement by turning upon their circular hubs as centers no matter how severe the steam-impact or vibration of the parts when the turbine is running at high speed.

For securing the nozzle 16 in place, their hubs are internally threaded, as at 18 for the reception of externally threaded steam-thimbles 19, the outer ends of which are formed with flanges 20 and which are introduced into the holes 12 aforesaid in the vertical face of the concentric offset 9 through assembly-holes 21 registering therewith and formed in the left-hand wall of the casing, the said assembly-holes 21 being normally closed by screw-caps 22 and serving also, in the initial construction of the steam turbine, to permit the introduction of the tools required for forming the holes 12 and the shallow recesses 13. As shown, the steam-thimbles 19 are formed with polygonal 105 passages permitting the introduction of a

polygonal tool by means of which they are screwed into place and removed.

The provision for positioning and securing in place the secondary nozzles 23 (Fig. 6) is the same in principle as already described for the primary nozzles 16. The nozzles 23 have positioning-hubs 24 entering equi-distant shallow, circular recesses 25 formed in the inner face of the right-hand wall of the steam-chamber 4 and receiving cap-screws 27 passed inward through the said wall, the inner face of which is formed with an annular positioning-groove 28 corresponding to the groove 14, intersecting the positioning-recesses 25 and receiving the positioning-fingers 27 of the nozzles 23.

By forming the nozzles 16 and 23 with positioning-hubs and positioning-fingers and inserting the same into positioning-recesses and positioning-grooves, as described, the nozzles are firmly held in place against lateral displacement by the energy of the steam or by the vibration of the parts of the turbine.

25 We claim:

1. A steam-turbine having one of the side walls of its steam-chamber formed with equi-distant positioning-recesses united by an annular positioning-groove, in combination with steam-nozzles having hubs enter-

ing the said recesses, and fingers entering the said groove, whereby the nozzles are positively held against lateral displacement.

2. A steam-turbine having one of the side walls of its steam-chamber formed with a 35 concentric offset containing an annular steam-passage and having its vertical wall formed with steam-holes, with positioning-recesses concentric with the inner ends of the said holes, and with an annular positioning-groove intersecting the said recesses, and the said side wall of the casing being also formed with assembly-holes registering with the said steam-holes in the said channel offset; in combination with nozzles 40 having positioning-hubs at their inner ends and positioning-fingers at their outer ends for respective insertion into the said positioning-recesses and groove, whereby the nozzles are positively held against lateral 45 displacement.

In testimony whereof we have signed this specification in the presence of two subscribing witnesses.

LUCIUS E. WHITON.
HENRY B. LEE.
